SPOOL OR REEL

Robert V. Olson and Bror A. Johnson, Attleboro,
Mass., assignors to Mossberg Pressed Steel Cor-
poration, a corporation of Massachusetts

Application February 28, 1938, Serial No. 192,933

4 Claims. (Cl. 242—123)

This invention relates to a spool or reel of a type formed of sheet stock; and has for one of its objects the provision of a spool or reel which will have no seam or joint at the corner between 5 the inner surface of the head and the barrel as often exists whereby to avoid wire which is assembled on the spool catching or the like in the crevice in such corner.

Another object of the invention is to provide 10 a spool the head and barrel of which may be assembled in a firm and rigid manner by welding whereby the parts become more or less homogeneous and a strong construction is provided.

Another object of the invention is the provision 15 of an arrangement whereby the joint between the head and body may be covered with a single plate which will assist in strengthening the joint while the plate at the same time assists the head in resisting strains due to expansion 20 of wire such as copper which has a different co-efficient of expansion than the steel of the spool, that the reel or spool may maintain its desired shape.

With these and other objects in view, the invention 25 consists of certain novel features of construction, as will be more fully described, and particularly pointed out in the appended claims.

In the accompanying drawing:

Fig. 1 is a sectional view through the new 30 structure;

Fig. 2 is an end view;

Fig. 3 is an exploded view of the several parts 35 which go to make up the end of the barrel and head of the spool;

Fig. 4 is a sectional view of a modified form 40 of reel.

It is found in the use of spools upon which wire is wound for drawing and annealing that where a joint exists at the corner between the 45 plane of the head and the barrel that the wire sometimes jams in the crevice of the joint. Also, it is found that copper wire having a different co-efficient of expansion than the steel of the spool expands to exert rather severe strains upon the head often flaring the head outwardly by reason of such strains; and in order to provide a construction by which the head is reinforced and no seam is formed at the joint and the reinforcing is such that the joint as well as the head 50 are reinforced at the same time, we have arranged for the barrel to have an out-turned flange to be received in the opening in the head with a plate positioned on the outer surface of the head and extending a sufficient distance 55 to strengthen the same and at the same time

cross or lap the joint thus formed that this joint may be strengthened at the same time; and the following is a more detailed description of the present embodiment of this invention, illustrating the preferred means by which these advantageous results may be accomplished:

With reference to the drawings, 10 designates the barrel portion of the spool or reel and 11 one of the heads. The barrel is of tubular construction preferably of seamless tubing, although this is not necessarily essential, with the ends of the barrel flanged as at 12 to extend out a substantial distance. The head 11 having a rolled periphery 14 for strength is provided with an opening 13 of a diameter to closely fit the flange 12.

A plate 15 of a size just smaller than the diameter of the rolled-in edge 14 contacts the outer surface of the plate and extends across the joint 16 formed at the end of the flange 12 and the edge of the opening 13. This plate also has a central opening 16 with an inwardly extending flange 17. A central tube 18 extends through the barrel and is provided with abutments 19 which engage the end 20 of the flange 17 while the end of this tube is flared outwardly as at 21 to assist in locking the strengthening plate 15 against the head by tying opposite end plates together.

A weld is performed at the joint 16 which secures the abutted surfaces of the flange 12 and the edge of the opening 13 together and also secures the plate 15 to the head 11 and the flange 12 at this location. This weld may be performed in any well-known manner either as a line around the entire length of the seam or by spots as at 23, shown in Figs. 1 and 2. Also, the head and plate 15 may be additionally joined at other spots as at 24 that there may be a firm secured relation between the head and plate.

In Fig. 4 the plate which we have provided instead of being in substantially a single plane with an in-turned flange at the center is now designated 25 and is drawn to extend inwardly as at 26 in a direction parallel to the axis of the spool, then bent to extend radially inwardly as at 27, then axially outwardly as at 28, then radially inwardly as at 29 and then axially inwardly as at 30, to provide an abutment for the projections 19 on the central tube 18 of the spool. This arrangement enables the joint at the edges of the flange 12 and opening 13 to be welded together and secured to the plate in the same manner as heretofore provided while giving even firmer support to the barrel 10 and also to the central tubular member 18. This plate is secured to the head in the manner previously described.

We have referred above to the parts being secured by welding, but we desire it to be understood that we include by this term brazing or soldering or any equivalent means for uniting the parts so that they will not move one relative to the other.

The foregoing description is directed solely towards the construction illustrated, but we desire it to be understood that we reserve the privilege 10 of resorting to all the mechanical changes to which the device is susceptible, the invention being defined and limited only by the terms of the appended claims.

We claim:

15. 1. In a reel or spool of sheet material, a tubular barrel member having a radially out-turned flange adjacent its end, a head member comprising a plate having an opening therein receiving said flange with the flange and plate in the same plane and the rim of the flange meeting the edge of the opening, and an additional plate on the outer surface of said head member extending across the juncture of the flange and plate portion of said members and in contact with a portion of said flange, and means for securing said parts in such relative position.

20. 2. In a reel or spool of sheet material, a tubular barrel member having a radially out-turned flange adjacent its end, a head member comprising a plate having an opening therein receiving said flange with the flange and plate in the same plane and the rim of the flange meeting the edge of the opening, and an additional plate on the outer surface of said head member extending 25 across the junctures of the flange and plate portion of said members, and means for securing

said parts in such relative position comprising welds at spaced points along the juncture for attaching together the meeting edges and the plate.

3. In a reel or spool of sheet material, a tubular barrel member having a radially out-turned flange adjacent its end, a head member comprising a plate having an opening therein receiving said flange with the flange and plate in the same plane and the rim of the flange meeting the edge 10 of the opening, and an additional plate on the outer surface of said head member extending across the end of said tubular barrel member and the juncture of the flange and plate portion of said members, and means for securing said parts 15 in such relative position comprising welds at spaced points along the juncture and at positions radially outward from the juncture.

4. In a reel or spool of sheet material, a tubular barrel member having its stock deflected to provide a radially out-turned flange adjacent its end, a head member comprising a plate of a thickness substantially that of said barrel and having an opening therein receiving said flange with the rim of said flange meeting the edge of 20 the opening in said plate in abutting relation with their opposite surfaces substantially flush with each other along said juncture, an additional plate on the outer surface of said head member extending across the juncture of the 25 flange and plate portion of said members, and means for securing said parts in such relative position, said additional plate having a central opening providing a bearing.
